Patented Feb. 7, 1922.

FIG. 1

FIG. 2.

Inventor

Charles V. Wright,
Chas. J. Williamson
Attorney

UNITED STATES PATENT OFFICE.

CHARLES V. WRIGHT, OF TAMAQUA, PENNSYLVANIA.

SHARPENING TOOL.

1,405,730.

Specification of Letters Patent. Patented Feb. 7, 1922.

Application filed February 2, 1920. Serial No. 355,538.

To all whom it may concern:

Be it known that I, CHARLES V. WRIGHT, a citizen of the United States, residing at Tamaqua, in the county of Schuylkill and State of Pennsylvania, have invented certain new and useful Improvements in Sharpening Tools, of which the following is a specification, reference being had therein to the accompanying drawing.

10 The object of my invention is to provide a simple and inexpensively made tool for sharpening the cutting rollers or members of devices such as pencil sharpeners of the well-known Boston type, without removing such cutting members and making use of the means for revolving them to effect the resharpening of them, and to this end my invention consists in a tool for the purpose stated having the characteristics defined or included within the scope of the appended claims.

In the drawings:—

Fig. 1 is a perspective view of a tool embodying my invention.

25 Fig. 2 is a side elevation thereof.

Referring in part to the case of pencil sharpeners which have rotary cutters so disposed as to provide the customary tapering point upon a lead pencil, I give to my sharpening tool, a rod-like form with a tapering end of a size and form enabling it to be thrust or placed in the pencil sharpener in the same relation to the rotary cutters thereof, that a pencil to be sharpened occupies, 30 and I provide the surface of the tapering part of the tool with a formation and give to it a hardness that will cut and thus sharpen the cutting edges or parts of the pencil cutting members of the pencil sharpener.

35 Referring to the particular tool illustrated in the drawing, it has a cylindrical shank 10, and at one end a taper 11, corresponding in form and size with the point which the pencil sharpener produces upon a pencil and 40 the periphery or surface of the taper 11 is made file-like as by means of fine screw thread 12, cut therein. Said tool is preferably made from soft steel and after the taper point or extremity is made and given the 45 file-like or cutting surface it is put through a hardening process to harden it to a degree sufficient to cut or grind the metal of the rotary cutting members of the pencil sharp-

ener. The end of the shank 10, opposite the point or taper 11, is formed or provided 55 with a handle to hold the sharpening tool stationary, which handle may consist of a simple diametrically extending pin or bar 13, inserted in a diametrically extending hole near the end of the shank. To use my 60 device, it is necessary simply to insert the point or tapering end into the pencil sharpening machine, just as would a pencil to be sharpened be inserted, and then turn the crank of the machine several times to 65 revolve the cutting rollers or rotary pencil cutting members thereof in contact with the abrading or cutting surface of the tool, the handle end of the latter being held to hold the sharpening tool stationary.

70 My invention, of course, is applicable to sharpening tools for resharpening the cutters of other implements, or cutting appliances, than pencil sharpeners and with which it is adaptable for use.

75 What I claim is:—

1. A sharpening tool for the rotary cutter of a pencil pointing machine, comprising a shank and a pointed member having a surface of a configuration and hardness that 80 will cut metal, said pointed member having a size and shape corresponding with the space between said rotary cutters.

2. A sharpening tool for the rotary cutter of a pencil pointing machine, having a 85 shank and a tapering portion of metal, with its periphery formed into a file-like surface, such tapering portion having a size and shape corresponding with the space between such rotary cutters.

90 3. A sharpening tool for the rotary cutter of a pencil pointing machine, comprising a cylindrical shank terminating in a round tapering point, the periphery of the point being an abrading or cutting surface, said shank and point being of one piece of metal, said point having size and shape corresponding with the space between said rotary cutters.

95 In testimony whereof I hereunto affix my 100 signature.

CHARLES V. WRIGHT.
